PRESSING PAD VENTILATING APPARATUS

Application filed October 11, 1928. Serial No. 398,907.

This invention relates generally to an improvement in laundry presses and particularly to means for ventilating the pressing pad in a manner to prevent moisture saturation.

- 5 In devices of this kind the pressing pad quickly becomes saturated with steam as the result of the pressing operation. It is, therefore, an object of this invention to provide a ventilating and moisture dissipating means 10 in which atmospheric or equivalent circulation through the pad is constantly maintained.

Features of the invention include the provision of a ventilating structure, along with 15 means for performing the ventilating function, as well as the details of construction shown.

Objects, advantages and features of the 20 invention will be set forth in the description of the drawings forming a part of this application, and in said drawings

Figure 1 is an end view illustrating the 25 application of the present invention to a laundry press;

Figure 2 is a longitudinal section substantially on line 2—2 of Figure 3;

Figure 3 is a plan view partly in section, corresponding to Figure 2; and

Figure 4 is a transverse section substantially on line 4—4 of Figure 3.

Figs. 5, 6 and 7 are diagrammatic views 30 illustrating the action of the press, in producing a gloss or hand-ironed finish of the goods.

The present invention provides a ventilating structure for a pressing machine, in which by a bellows-like action obtained as the result of arrangement of the parts, atmospheric air is forced through the pressing pad to dissipate moisture resulting from the pressing operation, and therefore in a manner to maintain the pad in substantially dry condition.

45 The numeral 1 indicates a lower stationary steam chest, numeral 2 the pad supporting cap, 3 the pad, and 4 the movable upper steam chest or pressing head. Numeral 5 indicates a suitable support for the lower presser head

50 1, and steam is introduced into the lower

presser head by means of pipe or pipes 6, in any suitable manner not herein shown.

The specific construction of the lower steam chest 1 does not form a part of this invention, but it will be understood that suitable intercommunicating steam circulation passages 7 are provided so that the chest can be steam heated uniformly throughout its entire upper surface. Arranged above the chest 1 for vertical motion is a pad support 3 having perforations 8 sufficient in number and/or area to establish proper ventilating circulation through the pad 3. The cap 2 is arranged in spaced relation to the marginal portion 9 of the lower chest. The cap may 65 be said to be related to the chest 1, as a lid to a box, except that all inner surfaces of the lid or cap are substantially always spaced from the corresponding inner surfaces of the support or chest 1, to maintain atmospheric 70 communication with the space between the elements and through openings or equivalent passages 8. The cap is held in spaced relation in any suitable manner and in such manner that it may move toward the support 1, 75 during the pressing operation. A specific means for mounting the pad-support is also claimed, along with the broader features of the combination.

In this instance, the lower chest 1 has the 80 form of a casting and includes upwardly opening sockets 10. A coil spring 11 is dropped into each socket and a headed screw bolt 12 passes loosely through the spring and through an opening 13 in the bottom of the socket and has threaded engagement as at 14 with a threaded opening 15 of the cap 2. The screws are used for adjusting the distance between the cap and the chest and for varying the tension on the springs, and their 85 heads are accessibly disposed at the bottom of the chest 1. By this arrangement, the cap is capable of universal movement and moreover, means is provided for varying the tension on the springs. In this instance, six 90 springs are employed arranged symmetrical- 95 ly at opposite sides of the longitudinal and transverse centers as best shown in Figures 3 and 4.

The gist of the invention is a moisture ex- 100

pulsion means adapted to maintain the pad of a pressing machine in substantially dry condition. Another feature is the employment of a bellows-like action for accomplishing the ventilating function, whereby a compression and suction action is had as result of motions of the pad support, respectively during pressing and upon release of press pressure.

10 Another feature pertains to the relation of the pivotal point 20 of the arm 21 to the surfaces 25, 26 of head 4 and pad 3, whereby during pressing, horizontal wiping actions between cap and head occur to give a hand-ironed finish to the goods. The difference is that between pressing a flat iron directly downwardly or vertically upon goods, without horizontal motion, and that of movement of the iron across the goods while under pressure.

15 The means provided for holding elements 1 and 2 in spaced relation and in comparative close proximity to one another is shown in Figure 2 of the drawings. The pivotal point 20 of the arm 21 is so related to the elements 4 and 2 that after engagement of element 4 with the pad 3 or goods thereon, continued downward motion of the arm 21 causes a relative horizontal motion between 20 elements 2 and 4 which gives the gloss finish to the goods, such as is given by a hand-ironing operation. Moreover, a leveling action is obtained which compensates for varying thickness of different portions of the goods 30 being pressed.

25 In Figures 5, 6 and 7, the arrows D—U represent the direction of head motion respectively down and up (close and open). The arrows D'—D², U'—U² respectively represent the pairs of reverse motions of the 35 cap with reference to the working face of the head and about the centers C—C'. The movement D' is downwardly and rearwardly; the movement D² is downwardly and forwardly; the movement U' is upwardly and rearwardly, and the movement U² is upwardly and forwardly.

30 Referring first to Figure 5, in which the rear margins of the working surfaces of the head and cap have just engaged: On continued motion in pressing direction, the cap 2 is tipped or swung about a center, represented by the letter C (which substantially corresponds to the opening 13, see Figure 2) 35 in the direction of the arrow D'. The cap is tipped to that direction until the parts assume the position shown in Figure 6, and the cap, therefore, undergoes a rearward movement. On continued downward movement of the head and until it arrives at the position shown in Figure 7, the cap is tipped in the opposite direction about the center C', in direction of the arrow D². This is a reverse or forward motion.

40 45 60 65 65 After the parts have assumed the position

in Figure 7 and on upward movement of the head, the cap follows the direction of the arrow U' about the center C'. (Another reversal, this time rearwardly). After the parts assume the position shown in Figure 6, and on continued upward motion and until the parts again assume the position shown in Figure 5, the cap swings in the direction U² about the center C. It is, therefore, seen that the cap is moved first in one direction and then in the opposite direction during the forward or closing movement of the press, and is also moved first one way and then the other, during the opening of the press. It is during the opening movement that the gloss finish to the goods is given, because at this time the goods is dry and the reverse-friction action is effective.

45 I believe myself the first to provide a lower stationary steam chest having a pressure equalizing cap at the top which is capable of leveling motion, and of automatically producing pad ventilation by the use of a substantially continuous passage which circumscribes the sides of the steam chest, and which establishes constant atmospheric communication with the space between a perforate pad supporting or working wall of the cap, and the corresponding face of the chest, and wherein the pivotal point of the arm, the working surface of pressing head and the working surface of the cap and the top surface of the buck are, during pressing operation, in horizontal planes which are close to one another.

50 Thus means is provided by which the normal action of the upper head on the cap 2 or against the goods laid upon a pad on the cap, causes ejection and suction action of air through the pad.

55 The spacing is maintained between the perimeters of cap and steam chest, as well as between upper surface of the buck and lower surface of the cap and the vertical walls of the cap are always in opposition to the vertical walls of the buck or chest. It is to be noted that the cap perforations are so arranged as to ventilate over its entire area, and over an area substantially equal to the area of the top of the chest or buck.

60 Another feature of the invention relates to the arrangement, in the atmospheric suction apparatus of this invention of the springs between the bottom of the cap and the upper portion of the buck or steam chest, and close to the pressing plane, along with the spacing which permits a rocking and wobbling motion, and which permits a certain amount of horizontal motion of the cap, which motion does not, however, interfere with the maintenance of a constant suction communication for the purposes set forth.

65 70 75 80 85 90 95 100 105 110 115 120 125 130 In order to obtain any useful suction effects for the purposes herein atmospheric communication must be constantly main-

tained, as well as a balanced suction column. To this end, the suction column must communicate with the horizontal chamber (resulting from the spaced relation of the perforated pad supporting wall of the cap and the working face of the steam chest) at all sides to obtain the proper degree of suction, as well as a suction balance. To this end, the suction passage has a circumscribing relation to the chest, and in this case substantially no obliteration of this continuous symmetrically arranged suction passage occurs, because of any rocking or lateral motions of the cap about its supporting and spacing springs.

On upward motion of the head 4, the springs act to assist in raising the element 2 which results in suction through the openings 8 which tends to dry the pad 3. In other words, pad drying action results from pressing and releasing motions of the element 4, as distinguished from the employment of extraneous devices, such as suction fans, etc.

Insofar as I am aware no one has conceived of an automatically operable ventilating apparatus in which the cap which holds the pad is perforated and in which the cap is related to the buck substantially as a loose lid of a box to the box, with the sides of the lid acting as stops to limit horizontal motion, and as ventilating-passage-forming elements.

Another feature of the invention is the provision of a stationary buck 5 which has a steam chest 7. The lower buck is hollow and stationary, while the element 2 is movable on this stationary steam chest, resulting in a wiping and polishing and hand-ironing action above described. With a stationary buck the steam pipes need no swinging joints.

40 I claim as my invention:

1. A device of the class described, comprising a steam chest, a lid-like element overlying the chest and having its top perforated, and having sides which continuously circumscribe and which are opposed to and disposed in spaced relation to the sides of the chest to form a continuous circumscribing ventilating passage communicating with the atmosphere, and means yieldably supporting the lid-like element with its top wall in spaced relation to the corresponding surface of the chest.

2. In a device of the class described comprising a steam chest, a lid-like element having a top having perforations, said top overlying the chest and arranged in spaced relation to the top of the chest to form with the chest a horizontal chamber, said lid-like element having sides opposed to and spaced from the sides of the chest to form a relatively continuous circumscribing ventilating passage which establishes atmospheric communication with said perforations through the chamber and means yieldingly supporting the lid-like element with its top in spaced rela-

tion to the corresponding surface of the chest, said yieldable means being adapted to allow light lateral motion of the cap.

3. In combination with a press having a steam chest having an upper face, a lid-like cap having a working wall overlying and spaced from the face and having a continuous depending flange opposed to the sides of the steam chest and spaced therefrom to permit free vertical and horizontal motions, but adapted to engage the chest to limit horizontal motions of the cap, compressible elements holding the cap in vertically spaced relation above the chest, said cap having perforations establishing atmospheric communication with the space between the cap and chest and said perforations being spread over an area of the cap substantially equal to the area of the upper face of the chest, a pressing pad overlying the perforations, and a presser arm engageable with the pad to depress the cap.

4. In combination with a press having a steam chest having a working face, a perforate lid-like cap having a working wall spaced from but close to said chest face, compressible springs holding the cap in said closely spaced relation, the sides of the lid being spaced from and opposed to the sides of the chest to form a continuous circumscribing passage, and a presser arm engageable with the cap to depress it and perform a pressing operation.

5. A pressing apparatus including a steam chest, a pad cap overlying the chest, compression springs engaging the chest and supporting the cap with its pad-supporting wall in spaced relation above the chest, linkage means securing cap to chest and adapted to limit upward motion of the cap against the action of the springs, and adapted to allow limited motions of the cap laterally in the plane of its working face, said press having a pivoted arm having a presser head engageable with the cap, the pivotal axis of the arm being so related to the head and cap that those margins of the working faces of the head and cap which extend in a direction parallel to the pivotal axis of the presser head engage before any other portion of the surfaces during forward or pressing movement of the head.

6. A pressing apparatus including a steam chest, a pad cap overlying the chest, compression springs engaging the chest and supporting the cap with its pad-supporting wall in spaced relation above the chest, bolts rigidly attached to the cap and passing loosely through openings in the wall of the chest and having enlargements as stops which limit upward motion of the cap against the action of the springs, said press having a pivoted presser arm having a head engageable with the cap, the pivotal axis of the arm being so related to the head and cap that those margins of the working faces of the head and cap which extend in a direction parallel to the

pivotal axis of the presser head engage before any other portion of the surfaces during forward or pressing movement of the head.

7. A pressing apparatus including a steam chest, a pad cap overlying the chest and having its pad supporting wall normally spaced from the chest, compression springs engaging the chest and supporting the cap in said spaced relation, bolts attached to the cap and passing loosely through a wall of the chest and having enlargements which limit upward motion of the cap against the action of the springs, said press having a pivoted presser arm having a head engageable with the cap, the pivotal axis of the arm being so related to the head and cap that the rear marginal portions of the working faces of the head and cap engage before any other portion of the surfaces, during movement of the head in pressing direction.

In witness whereof, I have hereunto set my hand this 5th day of October, 1929.

FRED CARL WILHELM.
